BATHING CAP OR THE LIKE

Maria Xtazy, 579 Hawthorne Place, Chicago, Ill.

Filed Feb. 19, 1958, Ser. No. 49,697

Term of patent 14 years

(Cl. D3—13)

Fig. 1 is a front view of a bathing cap or the like showing my new design;

Fig. 2 is a right side view thereof;

Fig. 3 is a left side view thereof;

Fig. 4 is a rear view thereof; and

Fig. 5 is an enlarged sectional view which may be considered as taken in the direction of the arrows substantially along the line 5—5 of Fig. 2.

I claim:

The ornamental design for a bathing cap or the like, substantially as shown.
